UNITED STATES PATENT OFFICE.

WILLIAM PRELLWITZ, OF EASTON, PENNSYLVANIA, ASSIGNOR TO INGERSOLL-RAND COMPANY, OF NEW YORK, N. Y., A CORPORATION OF NEW JERSEY.

MOUNTING FOR MINING TOOLS OR MACHINES.

1,023,595.

Specification of Letters Patent.

Patented Apr. 16, 1912.

Application filed May 6, 1909. Serial No. 494,446.

To all whom it may concern:

Be it known that I, WILLIAM PRELLWITZ, a citizen of the United States, and resident of Easton, in the county of Northampton and State of Pennsylvania, have invented a new and useful Mounting for Mining Tools or Machines, of which the following is a specification.

My invention relates to a mounting for mining tools, and is particularly well adapted to the mounting of a coal cutting tool in various advantageous positions on a primary support for floor, ceiling or breast cuts, while the operating handles for controlling the feed of the tool and its swing through its cutting arc are maintained in the same relative position one to the other and both within easy reach of the hands of the operator.

20 A practical embodiment of my invention is represented in the accompanying drawings in which,

Figure 1 is a view in side elevation of a tool mounted on a column in position for making what I am pleased to term a breast cut; Fig. 2 is an end view of the same; Fig. 3 is a top plan view of the same; Fig. 4 is a section in the plane of the line A—A of Fig. 1; Fig. 5 is a view in side elevation, showing the same tool in a position for a low down cut; Fig. 6 is an end view of the same; Fig. 7 is a similar view partly in section; Fig. 8 is an inner end view of the main supporting arm, showing the two sets of half bearings formed thereon; Fig. 9 is a view of the same in side elevation, showing also the bearing at the opposite end of the main supporting arm; Fig. 10 is a top plan view of the same, and Fig. 11 is an end view of 40 the same opposite that shown in Fig. 8.

The primary support which may conveniently be a column is denoted in the several figures by 1; the shell of the cutting tool by 2, the tool itself as a whole, by 3, its feed screw by 4, the handle for operating the feed screw by 5, the worm wheel for swinging the machine back and forth through its cutting arc, by 6, the worm for operating the worm wheel, by 7, and the handle for operating the worm by 8. These parts may be of any well known or approved form, my present invention being directed to the means for mounting the parts.

The shell 2 of the tool is supported by means of a tapered stem 9 in a tapered 55 socket 10, in which it is firmly locked by means of a bolt 11, as is usual. The socket 10 is formed in the end of a supporting arm 12 which is provided at its opposite end with a stem 13, preferably at an angle of 90° to 60 the longitudinal axis of the socket 10, the said stem 13 being provided with a shoulder 14 and with a tapered portion 15 by means of which it is drawn snugly into engagement with the wall of a corresponding 65 socket 16 in the rotary hub 17 of the worm wheel 6. The means for holding the stem 13 fast in the hub 17, consists in the present instance, of a screw 19 tapped into the end of the stem and passing through a cap plate 70 20 resting against the end of the hub. Any tendency of the cap plate 20 to rotate relatively to the stem 13, is overcome by a pin 21 set through the cap plate into the stem eccentric to the center of the cap plate and 75 stem.

The hub 17 is mounted in rotary adjustment in the plane of the worm wheel 6, in a bearing one-half of which is denoted by 22, and the opposite half of which, denoted 80 by 23, is formed in the end of the supporting arm 24. The portion of the hub 17 which rotates within the bearing 22, 23, is in the form of a segment of a sphere and the bearing is similarly formed to receive it. The 85 half bearing 22 is held in the desired relation to the half bearing 23, by means of bolts 25, 26, passing through the half bearings 22, 23 and along an annular groove 27 formed in the hub 17. The opposite end of 90 the supporting arm 24, to wit: that end toward the column 1, is provided with a half bearing 28, extending longitudinally at an angle of 90° to the longitudinal axis of the bearing 22, 23, and also with a half bearing 95 29 extending parallel with the longitudinal axis of the bearing 22, 23. The half bearing which co-acts with the half bearings 28, 29, is denoted by 30, and is clamped to the column 1 and to the companion half bearing 100 on the end of the arm 24, to wit: either the bearing 28 or the bearing 29, by means of bolts 31, 32. The half bearings 28, 29, in the end of the arm 24 are each provided with a pair of bolt holes as clearly shown 105 in Fig. 8, to receive the bolts 31, 32, and the

single half bearing 30 coöperates with either the one or the other of the half bearings 28, 29, at pleasure, to locate the arm 24 with its bearing 22, 23, either in a horizontal or 5 vertical position, as may be desired.

When located, as shown in Figs. 1 to 4 inclusive, the tool, denoted by 3, is in position to make a breast cut, while in the form shown in Figs. 5, 6 and 7, the arm 24 is 10 turned one-quarter around, thereby bringing the tool low down, as shown in Figs. 6 and 7, for a low down or floor cut. It is obvious that the main supporting arm 24 might be turned a quarter way in the reverse direction, thereby raising the tool by sliding the support along up the column in 15 position to make a ceiling cut close to the top and also that the arm 24 might be completely reversed or turned a half revolution 20 instead of a quarter, in either direction, if so desired.

It will be observed that in supporting the tool in these various advantageous positions, there is no part of a bearing or additional fastening required, identically the 25 same parts being used whatever may be the position required; and it will furthermore be observed that whatever the position which the parts may assume in rotating the 30 main supporting arm 24 and clamping it to the column, the handles for feeding the tool and for swinging the tool back and forth through its arc cut, will be maintained in the same relative positions, always within 35 convenient reach of the single operator to manipulate them. It will be further noted that the joint between the arm 12 and the arm 24 is in the nature of a ball and socket joint and serves, when the primary support 40 1 is, for any cause, somewhat out of a true vertical position, to provide for the adjustment of the stem 13 of the arm 12 to a true horizontal or true vertical position. Attention is also called to the position of the 45 operating tool with its longitudinal axis in the plane of the longitudinal axis of the supporting stem 13 of the arm 12, whereby lateral or twisting jar or strain is minimized.

In using the word "tool" throughout the 50 specification and claims I intend to include such devices as are commonly called machines, as well as the simpler form referred

to sometimes as tools and sometimes as machines.

It is obvious that changes might be resorted to in the form and arrangement of the several parts without departing from the spirit and scope of my invention; hence I do not wish to limit myself strictly to the structure herein shown and described, but 55 60

What I claim is:

1. A mounting for a mining tool comprising a main supporting arm and a shell supporting arm, the main supporting arm being provided with a plurality of half bearings 65 at one end for engaging a primary support and a half bearing at its opposite end for receiving the shell supporting arm in swinging adjustment and half bearings and bolts arranged to coöperate with the half bearings 70 on the main supporting arm.

2. A mounting for a mining tool comprising a main supporting arm provided with a plurality of half bearings at one end and with a half bearing at the opposite end, a 75 shell supporting arm provided with a socket at one end and a stem at the opposite end extending at right angles to the socket, a worm wheel provided with a hub in which the said stem is seated, and half bearings 80 and bolts arranged to coöperate with the half bearings on the arm.

3. A mounting for a mining tool comprising a shell supporting arm, a main supporting arm and a worm wheel hub, the shell 85 supporting arm being provided with a shoulered stem seated within the worm wheel hub, the said worm wheel hub being formed as a segment of a sphere and provided with an annular groove and the main supporting 90 arm being provided with a half bearing fitted to receive said hub, a half bearing arranged to co-act with said half bearing on the main supporting arm and bolts passing through the said half bearings and the 95 groove in the hub.

In testimony, that I claim the foregoing as my invention I have signed my name in presence of two witnesses, this fourth day of May 1909.

WILLIAM PRELLWITZ.
